UNITED STATES PATENT OFFICE.

SAMUEL B. MURDOCK, OF CHICAGO, ILLINOIS, ASSIGNOR TO THE AMERICAN COTTON OIL COMPANY, OF NEW YORK, N. Y., A CORPORATION OF NEW JERSEY.

PROCESS AND APPARATUS FOR SHREDDING SOAP.

Application filed September 9, 1919. Serial No. 322,695.

To all whom it may concern:

Be it known that I, SAMUEL B. MURDOCK, a citizen of the United States, residing at Chicago, in the county of Cook, State of Illinois, have invented certain new and useful Improvements in Processes and Apparatus for Shredding Soap; and I do hereby declare the following to be a full, clear, and exact description of the invention, such as 10 will enable others skilled in the art to which it appertains to make and use the same.

This invention relates to improvements in the production of soap flakes, and more particularly to the production of soap flakes 15 which are made up in part or in whole of soap shreds of an elongated and irregular character.

It has heretofore been proposed to produce comminuted soap in the form of soap 20 powder, and also in the form of flat flakes or scales. The improved soap flakes of the present invention are distinguished from the common forms of soap powder, and also from flat flakes or scales, by the irregular 25 and elongated, twisted and shredded character of the soap particles, due to the novel and improved method of their production. The present invention includes both the improved process, and the improved product 30 as a new product.

In the preferred embodiment of the invention, the soap is of a high grade, and of the character adapted for toilet purposes, made up essentially of pure soap with such 35 additions thereto as are common in high grade toilet soaps.

The process of the present invention involves subjecting the soap, containing a 40 moderate amount of water, and while in a warm liquid state, to the shredding action of a series of high pressure, superheated steam jets, so that the soap is sprayed and shredded, preferably in the form of elongated, twisted shreds. The thus sprayed 45 and shredded soap is permitted to fall through a considerable distance and is thereby deprived of part of its moisture content. The product can be still further dried, if desired, to give a product of the proper 50 water content desired in the finished commercial product.

The invention will be further illustrated by the following more specific description of certain embodiments thereof, and of an apparatus adapted for the practice of the im-

proved process of the invention and for the production of the improved product.

In the accompanying drawing,

Fig. 1 shows, in a conventional and diagrammatic manner, an arrangement of apparatus adapted for the production of the improved product.

Fig. 2 is a sectional view of the nozzle.

Fig. 3 is a view showing the removable plug of the nozzle, and

Fig. 4 is a top view of this same plug.

In the apparatus illustrated, the liquid soap is contained in one or more tanks 1 having a suitable inlet 2 and compressed air inlet 3, and provided with a pressure 70 gauge 4. Such tanks will in practice be provided with a heating jacket or heating coil (not shown). The outlet pipe 5 at the bottom of the tank has a regulating valve 6 therein and leads to the nozzle 7, described 75 below, which is supplied with superheated steam from the superheater 9 through the pipe 8. The nozzle 7 is arranged to discharge into a tower 10 of appropriate height.

The soap is collected at the bottom of the 80 tower upon a belt conveyor 11 which carries it into the dryer 12.

The specific construction of a suitable form of spraying and shredding nozzle is illustrated in Figs. 2 to 4. This nozzle is 85 made up of an outer casing 13, surrounded by a steam jacket 14 having inlet and outlet pipes 15 and 16, and having within it an inner casing 17 to which the superheated steam pipe 8 is connected. This inner casing has a tapered seat 18 which receives the disc or plug 19, having short slots or helical 90 passages cut therein. The particular plug illustrated has a cylindrical portion 20 and square end 21, as well as the slotted or threaded portion 22 and the tapered end portion 23.

The construction and arrangement of the spray nozzle is such that the liquid soap is supplied thereto through the pipe 5 and forced down through the annular passage between the inner casing 17 and the outer casing 13 and discharged through the lower annular opening of this passage. The soap is preheated by means of the surrounding 100 superheated steam steam-jacket and by the superheated steam within the inner casing 17, and its temperature is correspondingly increased, with resulting increase in its 105 fluidity. The high pressure superheated 110

steam enters through the pipe 8 and is discharged through the slots or openings in the plug 19, in such a way that the numerous jets of high pressure steam are given a swirling motion. These jets of high pressure steam immediately expand upon leaving the helical or spiral steam passages, and they are brought into contact with the escaping soap in such a manner that the soap is sprayed and shredded, and a considerable portion thereof is converted into the form of elongated or twisted shreds.

In the practice of the process, the soap composition will be preliminarily prepared before it is subjected to the shredding action. For example, a charge of 1200 or 1300 pounds of kettle soap such as is used in high grade cake soap for toilet and other purposes, is run into the crutcher, and there is added to it about 30 pounds of sodium silicate, 20 pounds of water, and perfume, if desired, and the whole mass is then thoroughly mixed by about five minutes crutching, care being taken not to beat any appreciable amount of air into the soap. Steam is kept circulating through the crutcher jacket during this operation. When thoroughly mixed, the batch is transferred to the pressure tanks 1 which may conveniently be arranged at or near the top of the tower 10.

Steam of appropriate pressure is superheated in the superheater 9 and passed through the nozzle 7. When the steam has attained a temperature of about 400° F., the soap is forced by means of compressed air into the soap chamber of the nozzle and through the annular opening thereof, where it is subjected to the shredding action of the steam. The steam, as above noted, is discharged through a plurality of openings or jets with a swirling motion, and this steam, due to its high temperature and the manner in which it is introduced, and due to the liquid character of the soap and the manner in which it is supplied, will spray and shred the soap and convert it into a product of the character desired.

The shredded soap is discharged into the tower 10 and falls through the tower a considerable distance, for example, as much as 45 feet or more, and is then caught on the conveyor belt which carries it into the dryer 12. The soap is cut into elongated, irregular shreds rather than into lumps, because of the fact that the blast of fluid under pressure moves substantially transverse to the direction of movement of the film or stream of soap, but slightly inclined toward said direction. Thus each jet will separate an irregular shred from the moving film, as the stream of soap comes under the influence of the blast or jet, and, since such shred is spaced from the preceding shred, the shreds tend to hold such relative position during

their passage downward through the stream of cooling fluid. During such passage the shreds are dried and a protective coating of dry soap is formed, so that when finally the shreds are collected in a mass on the conveyor they will not stick to each other.

The moisture content of the soap, as it leaves the nozzle, may be, for example, about 31%. This moisture content is somewhat reduced during the passage of the soap downwardly through the tower, due to the drying action of the highly superheated steam, and to any drying current of heated air which may be passed through the tower, so that the soap, when it reaches the bottom of the tower, may have a moisture content of, for example, 25 or 26%. This content is still further reduced in the dryer to about 18 or 20%. The dryer may be of any appropriate construction and heated in any suitable manner, for example, by exhaust steam, to a temperature of about 120° F., while the product is being carried through it on the conveyor 11.

After drying, the product may advantageously be subjected to a screening operation to separate it into products of different degrees of fineness, for example, to remove therefrom the finer particles passing through a 40 mesh screen, and the coarser particles passing over a 5 mesh screen. The product may thus be sent over a shaking screen equipped with a 5 mesh over a 40 mesh screen, so that the coarse particles will go over the former, while the fine particles will go through the latter. The finer and the coarser particles may be separately collected and used, or they may be returned to the kettles. The intermediate product will then be the product that goes through the 5 mesh screen but does not go through the 40 mesh screen. Such a product will contain soap flakes of irregular size and shape, a very considerable proportion of which will be of an elongated or twisted and shredded character, so that the soap product may be properly described as a shredded product.

I claim:

1. A method of shredding soap, which consists in directing an expanding jet of high pressure superheated steam against a moving film or stream of molten soap, in a direction substantially transverse to the direction of movement of the stream but inclining in such direction whereby to separate irregular shreds of soap from the stream.

2. The method of atomizing soap and of producing a shredded product, which comprises supplying hot liquid soap to an annular nozzle and discharging outwardly against the annular stream of escaping soap expanding jets of high pressure superheated steam, the jets being discharged with a

swirling motion, whereby the soap is effectively shredded.

3. The method of atomizing soap and of producing a shredded product, which comprises subjecting liquid soap to the shredding action of a series of expanding jets of high pressure superheated steam, and permitting the shredded product to fall through a heated atmosphere, whereby its 10 moisture content is reduced, and a shredded product of lower moisture content obtained.

4. The method of atomizing soap and of producing a shredded product, which comprises supplying hot liquid soap to an annular nozzle, and discharging outwardly against the annular stream of soap expanding jets of high pressure steam superheated to a temperature of about 400°F., the jets being discharged with a swirling motion, 15 whereby the soap is effectively shredded.

5. The method of atomizing soap and of producing a shredded product, which comprises supplying hot liquid soap of high purity to an atomizing nozzle, shredding 20 the soap by subjecting it to the shredding action of a series of expanding jets of high pressure superheated steam, permitting the shredded soap to fall through a considerable space with resulting cooling and drying 25 thereof, subjecting the product to a further drying operation, and removing from the resulting product the finer and the coarser particles, to give a shredded product containing soap shreds of an elongated and 30 irregular character.

6. An improved atomizing apparatus for the atomizing and shedding of liquid soap, comprising an annular soap chamber having an annular discharge nozzle, means for supplying the soap thereto under pressure, 40 a central steam chamber and means for supplying high pressure superheated steam thereto, said steam chamber being provided with a series of discharge openings or passages arranged to discharge expanding jets 45 of the high pressure superheated steam outwardly against the annular soap stream with a swirling motion, whereby the soap is effectively atomized and shredded.

7. A method of shredding soap, which consists in directing a series of expanding jets of superheated steam moving on parallel lines, against a moving film of molten soap in a direction substantially transverse to the direction of movement of the stream, 50 but inclining in such direction, thereby separating the stream into irregular shreds, and passing the shreds through a heated gas thereby drying said shreds and forming a protective coating on the shreds so that 55 they will not stick to each other.

8. An improved spray dried soap product, consisting essentially of substantially pure soap in the form of flattened and irregular, elongated and twisted shreds, of a size between about five mesh and forty mesh.

In testimony whereof I affix my signature.

SAMUEL B. MURDOCK.
